UNITED STATES PATENT OFFICE.

JOSEPH P. DAVENPORT, OF WHEATON, ILLINOIS.

FOLDABLE BACK AND HEAD REST.

Application filed June 13, 1921. Serial No. 477,312.

To all whom it may concern:

Be it known that I, JOSEPH P. DAVENPORT, a citizen of the United States, and a resident of the city of Wheaton, in the 5 county of Du Page and State of Illinois, have invented certain new and useful Improvements in Foldable Back and Head Rests, of which the following is a specification.

10 This invention relates to improvements in foldable back and head rests adapted for use upon a bed or the floor, the several parts of which are cheaply constructed and are foldable within the smallest possible limits 15 consistent with their size for carrying and shipping purposes.

The object of my invention is to combine with a foldable back rest a detachably jointed foldable head rest, permanently pivoted 20 to the back rest and adapted to be folded between the side bars of the latter, which head rest flexibly yields to the pressure of the head of the occupant and in its operative position is fulcrumed upon the head 25 rest at a point between its pivotal connection therewith and its upper end.

With these ends in view, my invention finds embodiment in certain features of novelty in the construction, combination and arrangement of parts by which the said objects are attained, all as hereinafter fully described with reference to the accompanying drawings and more particularly pointed out in the claims.

30 In said drawings,—

Fig. 1 illustrates in side elevation a combined back and head rest in which my invention finds its embodiment.

Fig. 2 is a front elevation thereof.

40 Fig. 3 is a detail illustrating the folding movement of the back rest.

Fig. 4 is a side elevation of the head rest and back rest in their folded position.

Fig. 5 is a top plan view of the head rest.

45 Fig. 6 is a detail section taken on the line 6—6 of Fig. 1.

Similar characters of reference indicate the same parts in the several figures of the drawing.

50 The longitudinal side bars for the back rest preferably consist of angle bars 7—7, connected at intervals by flat bars 8 riveted to the side bars, as indicated at 9, and preferably curved inwardly to conform to the back of the occupant, the lower end of the side bars being bent to a rounded form, as

indicated at 9^a, to prevent tearing of the fabric upon which the back rest may be supported.

To the side bars above their lower ends 60 are secured base bars 10—10, preferably riveted thereto, but may be secured by means of a nut-bolt 11, the opposite ends of these base bars being connected by a cross-bar 12 secured thereto by means of a rivet 13, the 65 base bars being provided at intervals of their length with notches 14. The pivoting of the base bar above the lower end of the side bar provides a one point contact only for the base bar with its underlying support, and which, with the end bar, stabilizes 70 the structure as a whole.

Pivots secured to the inner opposing sides of the side bars, by means of rivets 75 16, are brace bars 15, connected at their opposite ends by means of a rod 17, projecting outwardly beyond the base bars 10, and having screw-threaded thereon (see Fig. 6) a nut 18, which nut, in connection with the brace bars 15, is adapted to straddle the 80 notches 14 for the rod 17 to enter any one of the several notches 14.

Projecting underneath the front surface of the side bars 7 are bars 19—19, pivotally riveted to the bar 7 at 20, which bars 19 85 converge toward their upper ends, where they are detachably connected by a cross-bar 21, pivotally but permanently secured at one end of the bars 19 by a flat-headed bolt 22 passing through the cross-bar 21 90 and the bar 19, the opposite end of the bar being secured to the other bar 19 by means of a flat-headed bolt 23, passing through the bars 21 and 19 and provided with a thumb-nut 24, as shown in Fig. 2, for convenience 95 in tightening the cross-bar in its operative position and conveniently disconnecting it for folding purposes.

In order that the link 15 may be folded within the side bars 7, these latter bars (see 100 Figs. 1 and 3) are cut away, as indicated at 25, in Figs. 1 and 3, for receiving the heads of the pivot bolts 18, which would otherwise be stopped by the opposing edge of the side bars 7.

When the side bars of the head rest are in their operative position, as indicated in Figs. 1 and 2, they are slightly sprung and fulcrumed on the upper cross-bar 8 of the back rest, which latter is adjusted, as shown 110 in Fig. 1, or at any other inclination, by shifting the rod 17 to engagement with some

one of the other notches 14 in the bar 10.

For folding the head and back rest, the bar 15 is first disconnected from the notches, followed by swinging the bars 10 downwardly in the direction indicated in Fig. 3, until said bars lie flat against the outer side surface of the bars 7—7, followed by swinging the bars 15 until they lie flat against the inner surface of the bar 7.

10 It is now to be observed that the nut-bolt 22 for the head rest, while somewhat tight, permits of the cross-bar 21 being forcibly swung on its bar 19, the thumb-screw 24 being for the purposes of tightening the cross-bar in its operative position and so that, for the purposes of detaching it, the thumb-nut must first be removed, following which the head rest is folded by first moving the bar 19, shown in Fig. 2, downwardly 20 to free it from the top cross-bar 8, then swinging it on its pivot 20 against the bar 7, as indicated by dotted lines in Fig. 2, followed by swinging the other bar 19, together with the top bar 20 to the same position 25 relative to the other side bar 9, as indicated by dotted lines in Fig. 2.

In short, my invention provides a foldable back and head rest, all of the hinged members of which are pivoted to the back rest and may be swung from their operative position to and folded within approximately the confines of the side bars for the back rest, and to a position not only providing for great compactness for packing purposes, 35 but for carrying by hand a foldable back and head rest from place to place.

As before stated, the side bars of the head rest are sufficiently flexible for them to be swung between and fulcrumed on the top bar of the back rest and so that when connected by their top bar 21, as before described, they will be frictionally held in their operative position and yieldable to the pressure of a head resting thereon.

45 The type of foldable back rest, such as I have herein shown and described, is intend-

ed to be placed upon a bed or upon the floor, for the purposes of an invalid or one desiring to be sustained in a comfortable position while reading.

50 So far as I am now aware, back rests of the character described have never before been provided with a distinctive head rest, and particularly a head rest which is foldable within the confines of the side bars of a back rest, and my invention is therefore not limited to the special details of construction of such a head rest or whereby it is adapted to be folded within and against the longitudinal sides of a back rest, and particularly 55 a back rest of the construction herein shown and described.

Having described my invention, what I claim and desire to secure by Letters Patent is:

60 1. A back rest, a base bar therefor, pivoted above the bottom end of the back rest, adjustable brace bars detachably connecting the back rest and base bar, and a head rest provided with side bars pivoted to the back rest and means detachably connecting the upper ends thereof whereby said back rest and base bar are supported at its ends only, and the back rest, head rest and said base bar are foldable within each other.

65 2. The combination with an adjustable back rest having spaced cross-bars connecting the side edges thereof, of a head rest provided with flexible side bars pivoted at one end adjacent the side edges of the back rest, a cross-bar for detachably connecting the opposite ends of said flexible bars, and whereby the pivoted side bars of the head rest are adapted to be moved between the cross-bars of the back rest and fulcrumed on 70 one of said bars.

75 In witness whereof, I have hereunto set my hand this 9th day of June, 1921.

JOSEPH P. DAVENPORT.

In presence of—

JNO. G. ELLIOTT.
